CLAIM

U.S. PATENT DOCUMENTS

The ornamental design for slide rail for a clamp, as shown and described.

DESCRIPTION

FIG. 1 is a front end, top and right side perspective view of the design;

FIG. 2 is a front end elevational view of the design, the back end being identical;

FIG. 3 is a right side elevational view of the design, the left side being identical;

FIG. 4 is a top plan view of the design, the bottom being identical; and,

FIG. 5 is a back end, top and left side perspective view of the design, in which the broken lines represent the item in use and form no part of the claim.
